UNITED STATES PATENT OFFICE.

HORACE E. SMYTHE, OF PITTSBURGH, PENNSYLVANIA, ASSIGNOR TO THE S. R. SMYTHE COMPANY, OF PITTSBURGH, PENNSYLVANIA, A CORPORATION OF WEST VIRGINIA.

CONTINUOUS FURNACE.

1,310,846.

Specification of Letters Patent. Patented July 22, 1919.

Application filed January 23, 1919. Serial No. 272,646.

To all whom it may concern:

Be it known that I, HORACE E. SMYTHE, a citizen of the United States, residing at Pittsburgh, in the county of Allegheny and State of Pennsylvania, have invented new and useful Improvements in Continuous Furnaces, of which the following is a specification.

My invention relates to continuous heating furnaces, preferably heated by gas.

One object of this invention is to provide a novel means for feeding metal articles, as tubes, billets, bars, and the like, through the furnace. Another object is to provide a feeding means whereby an indefinite number of articles, from one up to the maximum capacity of the furnace, may be fed through the furnace, it not being required that the articles contact one with another, as is necessary with many furnaces. Another object is to provide means whereby the air may be suitably and inexpensively preheated before entering the furnace.

Referring to the accompanying drawings, Figure 1 is a vertical longitudinal section of one form of my furnace, the section being taken on the line I—I, Fig. 3; Fig. 2, a horizontal section on the line II—II, Fig. 1; Fig. 3 is a vertical cross-section on the line III—III, Fig. 1; Fig. 4, a vertical cross-section on the line IV—IV, Fig. 1; and Fig. 5, a fragmentary view showing in vertical longitudinal section a portion of a furnace embodying a modification of that shown in the preceding views.

The furnace has the hearth 1, the roof 2, the sides 3 and 4, the front end 5, and the back end 6. The back end has the charging door 7 and the front end, the discharging door 8, for the metal to be heated. The front portion of the roof 2 is made double or hollow to provide the air flue 9, which has its forward end communicated by the inlets 10 with the front end of the furnace chamber 11. Air is fed to the flue 9 by one or more pipes 12 leading from a blower or the like 13.

14 is a gas-supply main connected to the chambers 15, the admission of gas to each chamber being controlled by a valve 16 (only one being shown, Fig. 1) operated by a chain or rope 17, which passes over the sheave 18. A pipe 19 leads from each valve

chamber 15 to a gas inlet 20 at each side 3 and 4, near the front end 5 and the air 55 inlets 10.

A short distance from the rear end of the furnace, for example, about one-fourth of the length of the hearth from the rear end, I provide the openings 21, each connected by a flue 22 leading up to the pipe 23 which conveys the waste or spent gases to a stack, not shown.

The hearth 1 of the furnace is composed of a number of spaced stationary longitudinal sections 24 with a longitudinally and horizontally movable section 25 between adjacent sections 24. The movable sections are channeled above and lengthwise and supported on the metal pieces 26 arranged in transverse rows below the hearth 1, each row being connected together by a cross-support 27, having near each end a downward extending lug 28. The lugs 28 are arranged upon the traveling girders or bars 29, tied together by the cross-bars 30. The connected bars 29 are pivotally connected by the links 31 to the piston 32 of the hydraulic or other power cylinder 33.

Beneath the bars 29, I place a number of transversely arranged rock-shafts 34, each provided at each end with a short arm 34' which is connected to an adjacent cross-bar 27 by a link 36. The ends of the rock-shafts are journaled in the bearings 37 supported on the pillars 38. The central portion of each shaft is provided with a downwardly extending arm 39 pivoted to the horizontal bar 40. The rear end of the bar 40 is supported by the link 41 swinging on the pivot 42, and connected by the links 43 to the piston 44 of the hydraulic or other power cylinder 45. The stationary sections 24 of the hearth are supported on the transverse girders or bars 46.

The commingling air and gas from the inlets 10 and 20 begin to burn at the front end of the furnace chamber 11 and flow rearwardly to the outlets 21 and the stack flue 23, the air in the flue 9 being preheated by the roof 1 in a very economical and efficient manner. In the form of my invention shown on Figs. 1 to 4, the articles 47 are fed lengthwise so as to lie in the depressions between the stationary sections of the hearth and over the movable sections thereof. The

articles are fed step by step along the hearth as follows: Power is applied to the piston 44 to cause the bar 40 to be moved to the rear, which causes the movable sections of the hearth to rise so as to lift the articles 47 above the stationary sections of the hearth. Then the piston 32 of the cylinder is actuated so as to move the bars 29 and the movable sections 25 toward the front 10 of the furnace. Then the piston 44 is moved, or allowed to move by the weight of the articles 47, to the right, the articles again resting upon the stationary sections of the hearth. Finally the piston 32 is moved back 15 to the right, bringing the movable sections of the hearth back to their rearmost positions, ready for a new cycle of operations.

I locate the outlets 21 a distance from the rear end of the furnace as aforesaid, in order 20 to provide a relatively cool place of rest for the articles 47, where the molecules thereof may return to their normal positions and be relieved from strain.

In Fig. 5 the movable members 25^a of the 25 hearth have transverse notches 48. The articles 47 are arranged transversely of the hearth. The movable members 25^a travel just the same course as the members 25. The articles are engaged by the notches along 30 which the articles 47 may roll, the notches having the bases inclined.

49 indicates a cleaning door through which entrance may be had to the pit beneath the hearth, where the operating mech-

anism for the members 25 is located. 50 35 is a door closing the rear end of the pit.

I claim—

1. In a heating furnace, a hearth comprising parallel stationary and movable members, the latter being arranged between the stationary members, upright links pivoted at one end to the movable member and oscillatable in directions parallel with the length of the said members, means pivoted to the other end of the links for 45 elevating the links so as to move the movable member above the stationary members, and means for causing the movable member to travel longitudinally and the links to oscillate while they support the movable 50 member in its elevated position.

2. In a heating furnace, a hearth comprising parallel stationary and movable members, the latter being arranged between the stationary members, upright links 55 pivoted at one end to the movable member and oscillatable in directions parallel with the length of the said members, shafts having arms pivoted to the other end of the links for elevating the links so as to move 60 the movable member above the stationary members, and means for causing the movable member to travel longitudinally and the links to oscillate while they support the movable member in its elevated position. 65

Signed at Pittsburgh, Pa., this 15th day of January, 1919.

HORACE E. SMYTHE.
